DISPLAY CASE FOR MEMENTOS OR SIMILAR ARTICLES

Paul Wurtz, Williams Bay, Wis.

Application August 30, 1956, Serial No. 42,790

Term of patent 14 years

(Cl. D80—5)

Fig. 1 is a perspective view of a display case for mementos or similar articles, showing my new design; Fig. 2 is a side elevational view thereof; Fig. 3 is a front elevational view of Figure 1; and Fig. 4 is a top plan view of Figure 1.

The medal shown in dotted lines in Fig. 3 is for purposes of illustration only.

I claim:

The ornamental design for a display case for mementos or similar articles, substantially as shown and described.
